(57) **CLAIM**

The ornamental design for a base for a quick-detach optics and accessory mounting system for firearms, as shown and described.

DESCRIPTION

FIG. 1 is a front perspective view of base for a quick-detach optics and accessory mounting system for firearms, showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a rear perspective view thereof.

The broken lines in the figure drawings represent unclaimed portion of the design only and form no part of the claim.

The portions including surface shading represent contour and not surface ornamentation.

1 Claim, 8 Drawing Sheets
